UNITED STATES PATENT OFFICE.

GEORGE COLLINS, OF CHICAGO, ILLINOIS, ASSIGNOR TO J. J. BLEADON, OF CHICAGO,
ILLINOIS.

DISCHARGE TUBE FOR ELECTRICAL APPARATUS.

Application filed September 30, 1920. Serial No. 413,805.

To all whom it may concern:

Be it known that I, GEORGE COLLINS, a citizen of the United States, and a resident of Chicago, in the county of Cook and State 5 of Illinois, have invented certain new and useful Improvements in Discharge Tubes for Electrical Apparatus, of which the following is a specification.

This invention relates to discharge tubes 10 for electrical apparatus and particularly for medico-electrical apparatus, whereby electrical discharges are applied to various parts of the body, for the treatment of skin diseases or the like.

Such discharges in many cases are effected 15 by inserting a vacuum tube having a terminal at one end thereof, into proper contact with a coil or other apparatus, the discharge passing along the vacuum tube and out 20 therefrom to the area to be treated. One of the objects of the present invention is to provide a discharge tube simple and economical in construction, whereby a varying 25 resistance to the discharge may be effected so as to modify the strength of the treatment.

The drawing is an elevation of the discharge tube, constructed in accordance with the invention of which it presents an illustrative form.

In the drawing; I provide a tube 1, preferably of glass, having a dumb bell shaped enlargement transversely mounted at its top and comprising two lobes 2 and 3. The 35 tube 1 is in open communication with the lobe 2 and a closure 4 applied in the restricted part of the enlargement, seals the two lobes 2 and 3 from each other. The tube 1 and the lobe 2 are exhausted from the 40 lower end of the tube 1, after which the metallic cap 5 and terminal 6 are mounted thereon. The tube 3 is separately exhausted through an aperture which when sealed appears as the nipple 7 in the drawing.

This tube may be inserted in an electric 45 coil or other suitable apparatus, contact being made through the metallic cap 5, discharge taking place from the terminal 6.

The discharge follows the vacuum as long 50 as possible before passing through the air to the area under treatment. Thus if the face or end of the lobe 2 be applied adjacent the skin, discharge will pass from the terminal 6 through the vacuum tube 1, 55 through the enlargement 2 and out the end

thereof. If, however, the opposite end of the dumb-bell shaped enlargement, the end of the lobe 3, be placed adjacent the area of the treatment, the discharge will pass substantially through the same path as before, and 60 in addition through the separate vacuum in the lobe 3. By these means an additional resistance is interposed in the path of the discharge which is correspondingly reduced to produce a milder treatment. 65

The selective use of either end of the dumb-bell shaped enlargement, combined with the possibilities for variation afforded by the adjustment of the generating coil afford a wide range of treatment. The 70 structure is exceedingly simple, economical to make and exceedingly convenient in its application, mere reversal of position of the dumb-bell shaped enlargement effects immediate substantial modification in region 75 of the treatment.

Having now described my invention, I claim:

1. A tube for electrical discharge for use 80 in medical treatment, comprising a plurality of separate vacuums, so arranged that one or more thereof may electively be interposed in the path of the discharge.

2. In electro-medical apparatus, a discharge tube comprising a shank, an enlarged 85 discharge bulb thereon and a closure between the shank and the bulb, the tube being exhausted on both sides of the closure.

3. In electro-medical apparatus, a discharge tube comprising a shank, an enlarged 90 discharge bulb, said bulb being constricted at the middle and there provided with a closure, said shank being connected on one side of said closure, and the bulb being exhausted on both sides thereof, whereby a 95 varying resistance to the discharge may be provided.

4. In electro-medical apparatus or the like, a discharge tube comprising a shank, an enlargement thereon of substantial dumb-bell form, having its axis transverse to the axis of the shank, said shank being connected to one lobe of the enlargement, the other lobe being sealed therefrom, and both lobes being exhausted. 100

5. In electro-medical apparatus or the like, a discharge tube comprising a shank, an enlargement thereon of substantial dumb-bell form, having its axis transverse to the axis of the shank, said shank being in open 110

communication with one lobe of the enlargement, the other lobe being sealed therefrom, the parts of the apparatus on opposite sides of the seal being separately exhausted.

5. 6. The method of making an electrical discharge tube, which consists in blowing an integral tube comprising a shank and an enlargement of dumb-bell form thereon, said shank being in open communication with

one lobe of the enlargement, forming a 10 closure in the narrow part of the enlargement, exhausting the apparatus from the fine end of the shank, and from the sealed lobe.

In witness whereof, I hereunto subscribe 15 my name this 9th day of September, A. D. 1920.

GEORGE COLLINS.
